UNITED STATES PATENT OFFICE.

WILLIAM J. REGAN, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPING-LOCKING MECHANISM.

1,222,993.

Specification of Letters Patent.

Patented Apr. 17, 1917.

Application filed December 12, 1916. Serial No. 136,495.

To all whom it may concern:

Be it known that I, WILLIAM J. REGAN, a citizen of the United States, residing at Pittsburgh, in the county of Allegheny and State 5 of Pennsylvania, have invented certain new and useful Improvements in Car-Coupling-Locking Mechanism; and I do hereby declare the following to be a full, clear, and exact description of the invention, such as 10 will enable others skilled in the art to which it appertains to make and use the same.

My invention relates to improvements in car couplers, and is especially designed to afford means for maintaining the coupler 15 lock in locking relation to the knuckle whenever the coupler head is tilted or rotated laterally from its normal position to any such extent as might induce an unlocking movement of the lock, as, for instance, when the 20 coupler is turned partially or completely over in dumping the contents of the car; and to this end my invention, generally stated, involves the combination with a coupler-head, its knuckle, and a lock which projects 25 outside of the coupler, of a plurality of pendant dogs pivotally mounted on the coupler-head on opposite sides of the projecting lock, and adapted to be brought into engagement with the lock member by a rotation of 30 the coupler-head.

In the drawings chosen for the purpose of illustrating my invention, the scope whereof is pointed out in the claims,

Figure 1 is a front elevation of a car coupler embodying my invention.

Fig. 2 is a side elevation of the coupler, a portion of its stem being broken off.

Fig. 3 is a plan view of the coupler as shown in Figs. 1 and 2.

Fig. 4 is a front elevation, the coupler having been turned upside-down or at an angle of 180° to the normal.

Fig. 5 is a detail view, in front elevation, of a modified form of my invention.

Like symbols refer to like parts wherever they occur.

I will now proceed to describe my invention more fully so that others skilled in the art to which it appertains may apply the same.

In the drawings, 1 indicates a coupler

head having a knuckle 2 pivoted thereon by a pivot pin 3. The knuckle has the usual tail piece which is engaged by the lock 4 to prevent outward rotation of the knuckle to 55 open position. In the illustrated embodiment of my invention the lock 4 is the usual vertically movable pin projecting through apertures in the top and bottom walls of the coupler-head, and is provided with an eye 60 5 or equivalent means of connection with the usual or any approved release rigging by means of which the lock is raised to release the knuckle in the uncoupling operation. Through the lower end of the lock 4, below 65 the bottom wall of the coupler-head, a cotter pin 6 or its equivalent is passed to prevent accidental withdrawal or loss of the lock.

On the under surface of the bottom wall of the coupler-head on opposite sides of and 70 adjacent to the opening through which the lower end of the lock projects are cast or otherwise formed ears or lugs 7, 7 on which are pivoted pendant pawls or dogs 8, 8 which are adapted to swing freely toward 75 and from the lower end of the lock member 4, and which, as shown in Fig. 4, are of sufficient length to engage the retaining cotter 6 and prevent an unlocking operation of said lock when the coupler head is rotated 80 laterally to such an extent as would tend to induce an unlocking movement of the lock 4.

Instead of having the pawls 8 arranged to engage the cotter 6 of the lock 4, the sides of the lower end of the lock-member may be 85 notched, or shouldered, as at 9, as shown in Fig. 5 of the drawing, to receive the free ends of the pawls.

I claim:

1. The combination with a coupler-head, 90 and knuckle pivoted thereon, of pendant dogs pivotally connected with the bottom wall of the coupler-head, and a lock which projects through the bottom wall of the coupler-head intermediate of the said dogs, 95 said dogs being adapted upon rotation of said coupler-head to engage and prevent unlocking of said lock.

2. The combination with a coupler-head and knuckle, of a plurality of dogs movably connected to the bottom wall of the coupler-head, and a lock which projects below the

bottom wall of the coupler-head between the said dogs and is provided with means for engaging said dogs to prevent an unlocking operation of said lock.

5 3. The combination with a coupler-head and knuckle, of a lock for retaining said knuckle in coupled position, and means for

preventing said lock from moving to unlocked position, said means being mounted upon the coupler-head and being adapted to engage said lock through a lateral rotation of said head. 10

In testimony whereof I affix my signature.

WILLIAM J. REGAN.
